UNITED STATES PATENT OFFICE.

HUGO MUNZER, OF PATERSON, NEW JERSEY.

DAMPER-REGULATOR.

1,048,090.

Specification of Letters Patent. Patented Dec. 24, 1912.

Application filed April 13, 1912. Serial No. 690,476.

To all whom it may concern:

Be it known that I, HUGO MUNZER, a citizen of the United States, residing at Paterson, in the county of Passaic and State of New Jersey, have invented certain new and useful Improvements in Damper-Regulators, of which the following is a specification.

This invention relates to damper regulators for steam boilers and particularly to 10 damper regulators of the kind wherein a body of water, interposed between the boiler-water and the moving element of the motor of the regulating apparatus, serves to impart movement to said element as it is displaced upon changes of pressure within the boiler.

The invention consists in a damper regulating apparatus of the kind indicated having a novel means whereby the apparatus 20 can be adjusted to accomplish the closing action of the damper at different boiler-pressures.

In the accompanying drawings, Figure 1 is a front elevation of a boiler provided with 25 the improved damper regulating apparatus, a part of the boiler being broken away, and Fig. 2 is a side elevation, partly in section, of the motor including part of the apparatus shown in Fig. 1.

30 In the drawings the steam generator shown comprises, with a furnace having a fire-door *a* and an ash-pit door *b*, a boiler *c*. Part of the boiler is shown broken away to indicate the average level which is assumed by the water in the boiler, *d* being the usual water column communicating with the interior of the boiler above and below said level and having the water-gage *e*.

f is the smoke-pipe. *g* and *h* are dampers 40 in the ash-pit door and the smoke-pipe, respectively.

i in Fig. 1 is the motor. It is preferably arranged more or less above the maximum water level in the boiler, so that its moving 45 element is subject only to the moving influence of steam generated in the boiler; this, however, is not essential. The preferred form of this motor is that shown in Fig. 2 where *j* is an upstanding pipe having attached to or formed on its upper end a head *k* to which is attached the fluted or bellows-like extensible chamber *l* which is closed at its upper end and communicates at its lower end with the pipe. Housing 50 this chamber *l* and serving to support it upright is the rigid cylinder *m* whose upper

closed end rests on the top of chamber *l* while its lower end carries an apertured guiding head which fits over pipe *j*. Upon a fluid passing through pipe *j* into the chamber *l* it will extend the same upwardly and so raise the cylinder *m*.

n is a suitable means, such as a chain extending over pulleys *o*, for transmitting the movement of the cylinder *m* to the dampers *g* and *h*.

The water column *d* has the usual water-level indicating means in the form of pet-cocks *d'* and *d''*. From a point between these two pet-cocks a pipe *3* is tapped into 70 the water-column, being then extended downwardly approximately as far as the bottom of the boiler, and then upwardly, terminating in a tubular system or structure *3'* which may be thus described: 4 and 75 5 are two upright pipes connected at several elevations by the pipes *6* each having a cut-off valve *7*. Pipe *4* forms an extension of or may be connected with the upper end of pipe *3*. Pipe *5* may be connected with the 80 upstanding pipe *j* of the motor through the medium of a T-joint *8*. The T-joint may be connected with the pipe *3* by the pipe *9* which has a check-valve *10* opening toward pipe *3*. Thus, the conductor formed by pipe 85 *3* and parts *4*, *5* and *6* is one which is branched, having a return by-pass *(9)* around its branched portion.

Operation: It is not material how the water-trap formed by the downwardly 90 re-bent pipe *3* is supplied or replenished in the broad aspect of this invention; preferably, however, and as herein shown, these are accomplished from the water in the boiler whose level will usually be kept above 95 that where pipe *3* is tapped into the water-column. Changes of pressure in the boiler produce flow of the water trapped in pipe *3* into or out of actuating relation to the moving element of the motor. In its flow 100 toward the motor it passes from pipe *3* through pipes *4*, *6* (one or more of them, as will appear) and *5* into the motor; in its return flow it passes through by-pass *9*, opening the check valve *10* in order to do so. 105 As the moving element of the motor moves, so the damper or dampers move to regulate the draft of the furnace, as will be obvious. According as the first, or first and second, or first, second and third valves *7* (from the bottom) are closed, so the height to 110 which the trapped water must be elevated

- before it can reach the motor is varied, involving the advantage that in this way the apparatus can be adjusted to accomplish the closing action of the damper at different pressures. The check valve 10 causes the proper functioning of this adjusting means of the apparatus and permits the ensuing return of the water from the motor to the pipe 3 in a way which is substantially direct and which, at once the pressure in the boiler ceases to operate to drive the trapped water relatively outwardly, leaves the moving element of the motor to return substantially unimpeded.
- Having thus fully described my invention, what I claim as new and desire to secure by Letters Patent is:—
1. In combination, with a boiler, a furnace and a damper for the furnace, a damper-regulating fluid-motor having its moving element operatively connected with the damper, a fluid conductor leading from the boiler to the motor, comprising differently elevated tubular branches situated between

the boiler and motor, and containing a liquid between the boiler and said branches, and a cut-off valve in each branch, substantially as described.

2. In combination, with a boiler, a furnace and a damper for the furnace, a damper-regulating fluid-motor having its moving element operatively connected with the damper, a fluid conductor leading from the boiler to the motor, comprising differently elevated tubular branches situated between the boiler and motor, and containing a liquid between the boiler and said branches, a cut-off valve in each branch, said conductor having a return by-pass, extending around said branches, and a check-valve in said by-pass opening away from the motor, substantially as described.

In testimony whereof I affix my signature in presence of two witnesses.

HUGO MUNZER.
